United States Patent Office.

A. JUSBERG, OF GALVA, ILLINOIS.

Letters Patent No. 70,000, dated October 22, 1867.

IMPROVEMENT IN PUMPS.

The Schedule referred to in these Letters Patent and making part of the same.

TO ALL WHOM IT MAY CONCERN:

Be it known that I, A. JUSBERG, of Galva, in the county of Henry, and State of Illinois, have invented new and useful improvements in "Pumps;" and I do hereby declare that the following is a full, clear, and exact description thereof, which will enable others skilled in the art to make and use the same, reference being had to the accompanying drawings, forming part of this specification.

Figure 1 is a transverse vertical section and part elevation taken in the plane of the line $x x$, fig. 2.

Figure 2, a horizontal section, taken in the plane of the line $y y$, fig. 3.

Figure 3, a vertical section, taken in the plane of the line $z z$, fig. 2; and

Figure 4, a transverse vertical section, taken in the plane of the line $v v$, fig. 2.

Similar letters of reference indicate corresponding parts.

The improvements in pumps embraced in the present invention can be applied to either single or double-action pumps, and the invention consists—

First. In so arranging the several valves and the communicating passages, both inlet and outlet, to the piston or plunger-cylinder of the pump, that the water or other liquid will be drawn into the same, both in the downward and upward movement of the plunger, so that as it is discharging before the plunger in either case, whether moving up or down, it is receiving behind or back of the plunger, whereby, even with a single plunger, or piston and barrel, or cylinder, a continuous stream or discharge of water is secured.

Second. In so connecting two or more pump-cylinders, both of which are provided with valves and communicating passages, according to the first part of the invention, that only one supply and only one discharge pipe are required.

Third. In forming at each end of the pump-cylinder, a chamber or box, similarly so partitioned that the water will be divided and carried, or allowed to pass, to both ends of the cylinder, if only one is used, and similarly to the other cylinders if two or more are connected.

Fourth. In the combination of side cylinders to the plunger-cylinder or cylinders of the pump, the one for the passage of water to the pump-cylinders, and the other for the discharge of the water therefrom.

In addition to the above, I have also made other improvements in the detail construction of the pump in its various working parts, that for the successful and efficient operation of the pump are most important, as will be obvious from the description to be hereinafter given.

A A, in the drawings, represent two cylinders or barrels, of similar shape and size. These cylinders A are placed the one alongside of the other, and by means of continuous head-plates B B² are closed at their upper and lower ends respectively; the head-plates being held together by means of suitable tie-rods or bolts C, extending from one to the other, with nuts screwed therein. The joints between the head-plates and cylinders are sealed with a packing, D, of any suitable kind applied thereto. At each end of the cylinder A, outside of their head-plates B B², a chamber, E, is formed, by means of a plate, F, applied thereto, that is hollowed or cut out upon its face toward the cylinder-heads. These chambers E are partitioned along their length, or in the plane, or a parallel plane between the centres of the pump-cylinders, so as to form two chambers in each, which, for a more perfect comprehension of the description of the operation of the pump to be hereinafter given, have been lettered, in the case of the chambers at the upper and lower ends of the cylinders, respectively, G and G², and G³ and G⁴. H H², openings in the lower head-plate B² to cylinders A, two to each cylinder. The openings H communicate into the chamber G, and the openings H² with the chamber G², each opening being provided with a valve, I, that in the openings H are arranged to open into the pump-cylinders, and in the openings H² to open into the chamber G². J J², openings in the upper head-plate B to cylinders A, two to each cylinder. The openings J communicate with the chamber G³, and the openings J² with the chamber G⁴, each opening being provided with valve K, that in the openings J are arranged to open into the pump-cylinders A, and in the openings J² to open into the chamber G⁴. L, the supply pipe to the pump-cylinders. This pipe communicates with the chamber G², at the lower end of the pump-cylinders. M, the discharge pipe for the water from the cylinders A. This pipe communicates with the chamber G⁴ at the upper end of the cylinders A. N N², two cylinders or chambers, interposed between the cylinders A, which chambers, at their upper and lower ends, are closed by the head-plates B B², in common with the cylinders A. The cylin-

der N, at its lower end, communicates through an opening, O, with the chamber G², and at its upper end through an opening, O², with the chamber G⁴. The cylinder N² communicates at its lower end through hole O³ with the chamber G, and at its upper end, through hole O⁴ with the chamber G³. P, the plunger or piston-heads for the cylinders A, one to each cylinder, wherein they are suitably packed, to move air and water-tight. O, the rods to the plungers P, from which they pass out through the head-plate B, and are hung by their upper ends to pitman-rods R², that by boxes are hung to the cranks S of the horizontal shaft U. This shaft U turns in bearings V of upright frames W, and with its gear-wheel X engages the gear-wheel Y of the driving or operating-shaft Z.

Having thus described in detail the construction and arrangement of the several parts, I will now explain their operation or connection with each other.

As the driving-shaft turns, the two pistons P are made to move up and down within the cylinders A, the one after the other, when, as the one descends and the other ascends, the water before them in each case is forced out of the cylinders in the first instance, through the valve I, opening outward from such cylinder into the chamber G, and from thence up through the cylinder N² into the upper chamber G³, and thence down into the same cylinder upon the other side of the piston or plunger thereto, and in the other instance, up through the valves K of such cylinder opening outward and into the chamber G⁴, and from thence into the discharge pipe M. The pistons having thus completed their stroke in the one direction in each case within the cylinder, by continuing to turn the driving-shaft, the plunger, which in the first instance moved downward, now moves upward, and the reverse with the other plunger, the water in the first case, above the piston, passing out of the cylinder into the discharge pipe, through the upper valves K, opening into the chamber G⁴; at the same time drawing in water from below, through the valves I, suitably opening therefor, while, in the other case, the water below the piston is being forced through the valve below into the chamber G, and from thence up through the cylinder N² into the chamber G³, and through the valve K, in the same cylinder, down into the same above the piston or plunger.

From the above description it is plain to be seen that a continuous stream of water is of necessity discharged from the discharge pipe to the pump. To make the piston-rods water-tight in their movement through the heads to the cylinders A, I construct a box packing, A², around the same, whereby the water is prevented from working through the same, as the pistons move up and down.

I claim as new, and desire to secure by Letters Patent—

The arrangement of the pump-cylinder A, cylinders N N², chambers G G² G³ G⁴, valves I K, plates B B², and F, and forming chambers E, all operating as described for the purpose specified.

The above specification of my invention signed by me this   day of   1867.

A. JUSBERG.
